UNITED STATES PATENT OFFICE.

JOHN W. BUNN, OF KANSAS CITY, MISSOURI.

LOCOMOTIVE-HEADLIGHT.

1,101,118.

Specification of Letters Patent. Patented June 23, 1914.

Application filed January 16, 1913. Serial No. 742,445.

To all whom it may concern:

Be it known that I, JOHN W. BUNN, a citizen of the United States, residing at Kansas City, in the county of Jackson and State of Missouri, have invented certain new and useful Improvements in Locomotive-Headlights, of which the following is a specification.

The present invention relates to head-lights adapted to serve high speed vehicles traveling upon a fixed right of way where it is necessary that the illuminating effect extend a considerable distance in advance of the vehicle which carries it, in order to 15 warn trespassers upon the right of way and assist the observation of the engineer.

The object of the present invention is to develop a high efficiency headlight illuminated by combustion of readily obtainable 20 grades of hydrocarbon fuel, and a burner preferably of tubular construction with a reflector and a lens is employed. The reflector is of spherical concave type spaced from the burner a distance to leave the 25 burner in the vertical plane of its spherical center, but adjusted vertically to leave the burner beneath the axis of the reflector, so that the reflector produces a real image of the flame in the same vertical plane with 30 the burner, but sufficiently above and in inverted position to cause the flame of the image to merge with the flame of the burner and thereby produce, in effect, a duplication 35 of that portion of the area of the flame which is presented toward the path of illumination, and correspondingly increasing the illuminating power of the beam. The lens is of Fresnel type with a definite focal 40 point from which it is adapted to parallelize the rays of light, but located at a less distance from the plane of the true flame and image than its focal distance, with the double advantage of receiving a greater proportion of the light and delivering the same 45 on lines slightly diverging from parallelism in order to enlarge the beam to the necessary area of illumination at the extreme distance required, and at the same time to avoid too sharp a definition between the light area and 50 the surrounding darkness. Coupled with the aforesaid conditions of light source, reflector and lens, are certain constructional characteristics of the lamp body.

The invention will be fully understood upon reference to the accompanying drawings, in which—

Figure 1 is a side elevation of a complete locomotive headlight to which the present invention is applied; Fig. 2 is a front elevation of the same; Fig. 3 is a vertical longitudinal section of the same; Fig. 4 is a transverse section of the same; Fig. 5 is a horizontal section on the line 5—5 of Figs. 1, 2, 3 and 4, and Fig. 6 is a vertical section of the ventilator on an enlarged scale. Fig. 7 is a diagrammatic view.

1 represents the housing of the headlight, with angularly presented translucent number panels 2; 3 is the movable side closure carrying one of the number panels 2, as well as the hand hole 4 and inspection opening 5; said side closure being made to conform to the approximately cylindrical transverse section of the housing 1 and being hinged at 3^a on the front wall and secured by a latch 3^b to the back wall; 6 is the movable front closure carrying the lens 7, the guard 8 and removable shield 9; and 10 is the ventilator.

The end closure 6 is hinged on one side at 6^a and provided on the other side with a latch 6^b. It comprises all of the front wall, with the exception of a narrow frame provided to receive it, which frame is substantially circular in conformity with the front 85 closure, except at bottom where it intersects the supporting base. The lens 7 is of concavo-convex form, with concentric circular Fresnel prisms which give to the lens a comparatively short focal distance with long 90 projecting power and thereby adapt it for location in close proximity to the light source with consequent increase in intercepted light area. The shield 9 fits within the guard 8 and is provided with upper and lower retaining tongues 9^a, 9^b, projecting through apertures in the guard 8 and of such length that by raising the shield, the lower tongue 9^a is released, so that the shield 95 may be swung outwardly and downwardly 100 for removal. Hangers 9^c on the back of the headlight receive the shield 9 when not in use. The number panels 2 are carried by light boxes 2^a projecting from the cylindrical walls of the housing 1 and having forwardly and inwardly inclined faces recessed

to receive suitable glazing 2^b; also a confining frame 2^c hinged at 2^d and adapted to be secured in closed position by jam-nut 2^e. The sight opening 5, while preferably closed, is also adapted to be closed by a slide 5^a having a retaining clip 5^b. The hand hole 4 is provided with a closing slide 4^a preferably mounted on the inner wall of the housing.

10 The ventilator 10, as shown more clearly in Fig. 6, comprises a hood 10^a hinged at 10^b upon a pyramidal base 10^c and provided with a latch 10^d releasable to permit the hood to swing upwardly to give access to interior parts. Resting upon the pyramidal base independently of the hood 10^a is a wind screen comprising upper and lower perforated disks 10^e, 10^f, spaced apart to provide a chamber between them; the disk 10^e being seated within the upper end of the base 10^c and the disk 10^f being supported from the disk 10^e by means of the chimney flue 10^g, which stands on the disk 10^f and terminates in a flaring skirt 10^h forced into position within the cylindrical portion of the chimney flue and being thus easily removable. Disk 10^e is sprung into place in the annular groove provided for it on the chimney 10^g, or may else be made in two parts joined together. The hood 10^a, when closed, rests in contact with the disk 10^e besides providing tight side walls for the chamber between the disks, while above the disk 10^e, said hood is constructed with perforate side wall 10ⁱ and imperforate top wall 10^k providing an intake chamber for fresh air to support combustion. The flue 10^g extends through the top wall 10^k of the fresh air chamber and terminates in a contracted end 10^m within the cowl 10^h which comprises an expansion chamber 10ⁿ; a deflector 10° and a cap 10^r. The lower end of the flue 10^g is likewise provided with a deflector 10°. Resting upon the top wall 10^k and depending in protecting relation to the perforate wall 10ⁱ, is a guard 10^t. The ventilator thus constructed provides two concentric passages for the intake of air in support of combustion and the outlet of the products of combustion. The flaring skirt 10^h as well as the general shape of the pyramidal base directs the incoming air toward the side walls of the housing, cooling the parts and taking up heat preliminary to flowing inward at bottom and passing upward through the lamp to support combustion. The fresh air intake is thoroughly protected against air disturbances and the outlet flue for products of combustion is likewise guarded against down draft.

11 represents the light source which is preferably produced from a lamp 12 of tubular construction, supplied by oil duct 13 from a reservoir 14.

65 15 represents the reflector which is of true

spherical type, supported with vertical adjustment upon the posts 15^a and placed in such position that the light source 11 stands in the vertical plane of the geometrical center of the reflector but slightly below the axis, with the result that the reflector focuses in said plane, a real but inverted image of the flame, sufficiently above the true flame to avoid eclipsing the reflection and in effect producing a flame of double dimensions, or in other words, delivering to the lens 7, reflected rays which are substantially equivalent to the direct rays from the light source. The distance of the lens from the vertical plane of the true flame and image is slightly less than the focal distance, so that while the lens is constructed to parallelize rays emitted from its focus point, it will deliver a beam of illumination that is slightly divergent and thus develop the necessary area of illumination at the distance where illumination is mostly needed. The lens has the further effect, probably due to such inaccuracies as are unavoidable in a lens that is molded and not ground, of dispersing some of the light on the outer edge of the projected beam and thus avoiding the objection of having too sharp a definition between the immediate area of illumination and the surrounding darkness, with the advantages already described.

16 represents the lamp chimney and 17 a sustaining guide for the upper end thereof, which is preferably constructed of a spiral winding on a rigid annulus, which latter extends from a yoke 17^a projecting upwardly from the reservoir. As shown in Fig. 5, the reservoir 14 is extended horizontally on either side of the lamp. This is for the purpose of extending the walls of the reservoir and increasing the cooling effect thereupon of the cool air drawn in through the ventilator. The oil is thereby kept in better condition.

Owing to the importance of having the reflector, the lamp and the lens in the particular relations described, and yet permitting the removal of the lamp and reflector for cleaning and adjustment, the lamp and reflector are supported upon a base 18 through the medium of standards 18^a, 18^b, and the base is in turn held in the guides 18^c, so that the lamp and reflector may be removed at will, but will always be returned not only in the proper relation to each other, but in the proper position relatively to the lens. An upwardly deflected portion 18^e in the base 18 provides a panel for the admission of some air through the perforations 1^a in the bottom of the housing 1. The bottom and back of the housing are constructed of three laminae, namely, the inner sheet of metal 1^a, the outer sheet of metal 1^b, and the intermediate sheet of heat insulation 1^c. The purpose of this construction is to pro-

tect the lamp from heat radiated from the smoke box of the locomotive.

19 represents a holder adapted to receive the lamp chimney in inverted position when not in use.

I claim:—

1. In a headlight, a concave spherical reflector placed with the axis horizontal, a concave lens of the Fresnel type, having its axis in alinement with the axis of said reflector, the focus of the lens being situated between the reflector and the reflector focus, a light source producing an upright flame, the upper edge of said flame being substantially in said axis and the axis of the flame being in the focus of the reflector.

2. In a headlight, a concave spherical reflector placed with the axis horizontal, a concave lens of the Fresnel type, having its axis in alinement with the axis of said reflector, the focus of the lens being situated between the reflector and the reflector focus, a light source producing an upright flame, the upper edge of said flame being substantially in said axis and the axis of the flame being in the focus of the reflector, whereby said reflector will throw an inverted image of the flame on said lens without the reflection being eclipsed.

3. In a locomotive headlight, the combination of a housing, parallel guides in said housing, a lamp base fitted to said guides and removably secured thereby in said housing, a reservoir supported upon said base with laterally extending sides, posts projecting from the sides of said reservoir, a mirror supported on said posts, a lamp also mounted on said base in fixed relation to said mirror but entirely free therefrom, and a lens mounted upon the housing in

fixed relation to the guides which receive said base.

4. In a locomotive headlight, the combination of a housing, a reservoir mounted in said housing with a transverse portion and two longitudinal portions, a yoke extending upwardly from and supported by said longitudinal portions of the reservoir, a lamp located between the longitudinal portions of the reservoir, and adapted to receive a chimney, a lens in front and a reflector behind said lamp, and a chimney guide mounted upon said yoke above the lamp and free from said reflector, in position to receive the upper end of a chimney when applied to the lamp.

5. In a locomotive headlight, the combination of a suitable housing, a fuel burner or lamp, a reservoir for said lamp constructed with transverse and longitudinal portions, and a top ventilator for the headlight delivering air downwardly over the walls of the housing and between said walls and the transverse and longitudinal portions of the reservoir.

6. In a locomotive headlight, the combination of a housing, a fuel burner within said housing, a reservoir for said fuel burner constructed with transverse and longitudinal portions paralleling the walls of said housing and heat insulating material provided upon the walls of said housing.

The foregoing specification signed at Kansas City, Missouri, this 26th day of December, 1912.

JOHN W. BUNN.
